Primary Examiner — Sheryl Lane*(74) Attorney, Agent, or Firm* — Carrithers Law Office PLLC(57) **CLAIM**

The ornamental design for a planting tool, as shown and described.

DESCRIPTION

FIG. 1 is a perspective view of the planting tool showing my new design;

FIG. 2 is a front view with the rear view being a mirror image thereof;

FIG. 3 is a top view thereof;

FIG. 4 is a bottom view thereof;

FIG. 5 is a right side view with the left side view being a mirror image thereof; and,

FIG. 6 is a perspective view including a handle shown in phantom view.

The broken lines showing the handle and plunger show portions of the article and form no part of the claimed design.
